UNITED STATES PATENT OFFICE

HAROLD GREENHILL, OF CHICAGO, ILLINOIS

VENDING MACHINE

Application filed March 1, 1928. Serial No. 258,206.

My invention pertains to the general class of devices known as vending machines and particularly to the class of devices for vending articles and simultaneously therewith providing amusement for the prospective purchaser. An object of applicant's invention is the production of a device whereby articles may be vended automatically. A further object of applicant's invention is the production of an automatic vending device wherein amusement is provided simultaneously with the prospective sale. A further object of applicant's invention is the production of a vending machine for the purpose of stimulating sales and meeting competition with devices of a similar character. A further object of applicant's invention is the production of a combined vending machine and apparatus for improving marksmanship. A further object of applicant's invention is the production of a device simple in construction, of low cost, automatic in operation, durable and satisfactory for its intended purpose.

Many other objects and advantages of the construction herein shown and described will be obvious to those skilled in the art from the disclosure herein given.

To this end my invention consists in the novel construction, arrangement and combination of parts herein shown and described, and more particularly pointed out in the claims.

In the drawings, wherein like reference characters indicate like or corresponding parts:

- Fig. 1 is a top plan view of the device;
- Fig. 2 is a side elevation thereof;
- Fig. 3 is an end elevation;
- Fig. 4 is an end elevation opposite the end shown in Fig. 3;
- Fig. 5 is a section taken on line 5—5 of Fig. 2;
- Fig. 6 is a section taken on line 6—6 of Fig. 2;
- Fig. 7 is a section taken on line 7—7 of Fig. 1;
- Fig. 8 is a section taken on line 8—8 of Fig. 7;
- Fig. 9 is a section taken on line 9—9 of Fig. 7;
- Fig. 10 is a section taken, on line 10—10 of Fig. 3;
- Fig. 11 is a section taken on line 11—11 of Fig. 7;
- Fig. 12 is a section taken on line 12—12 of Fig. 7;
- Fig. 13 is a section taken on line 13—13 of Fig. 12; and
- Fig. 14 is a section taken on line 14—14 of Fig. 7.

Fig. 9 is a section taken on line 9—9 of Fig. 7;

Fig. 10 is a section taken, on line 10—10 of Fig. 3;

Fig. 11 is a section taken on line 11—11 of Fig. 7;

Fig. 12 is a section taken on line 12—12 of Fig. 7;

Fig. 13 is a section taken on line 13—13 of Fig. 12; and

Fig. 14 is a section taken on line 14—14 of Fig. 7.

Referring now to the drawings wherein a preferred embodiment of the invention is shown, 1 shows a hollow oblong upright casing provided with a plurality of glass panels 2 positioned as desired. The rear of the casing is provided with a door 3, the purpose of which will be hereinafter set forth. At the front of the casing is a coin ejector 4 extending inwardly into the casing. Below the coin ejector 4 and positioned on each side of the casing at the bottom thereof are receptacles 5 for catching the vended article as same is ejected from the machine. Above each receptacle 5 are shields 6 for the purpose of causing the vended articles to fall into the receptacle and otherwise shield same. At one side of the casing 1 is a receptacle 7 for the purpose of catching coins returned to the prospective purchaser through the aperture 8. Above the receptacle 7 and opposite the aperture 8 is a shield 9 for causing the ejected coin to fall into receptacle 7 and otherwise protect the aperture 8.

Referring now to Fig. 7, the glass panels 2 are shown secured to the inner walls of the casing 1 by means of a plurality of lugs 10. The coin ejector 4 is shown pivoted at 11 in the front of the casing by any suitable means such as a socket 12 and a ball 13, the ball 13 is secured to the coin ejector 4 by means of the shank 14. Above the coin ejector is a transparent panel 15 secured to the inner front wall of casing 1 by means of lugs 16. Spaced from the rear wall of casing 1 is a target 17 with an aperture 18 positioned centrally thereof. Aperture 18 is preferably elongated as shown in order to accommodate a coin allowing the same to pass therethrough.

About the aperture 18 are a plurality of concentric rings 19. The target 17 thus assimulates the customary target used in rifle and pistol practice. At the bottom of target 17 and in the space 20 between same and the rear wall of casing 1 is a chute 21 with an inclined bottom 22, said chute leading to the aperture 8 and is for the purpose of discharging coins falling therein through the aperture 8 into the receptacle 7 in order that same may be recovered by the prospective purchaser. Chute 21 may be of any form but preferably is shaped in such manner that the coin to be ejected will pass through the aperture 8 in a certain position in order that the aperture 8 may be no longer than necessary. In the form shown, the coin passes through aperture 8 on edge or in an upright position. This is accomplished by means of the converging wall 23 of chute 21. Between the target 17 and the coin ejector 4 is a sloping plate 24 which slopes downward in the general direction of the target 17. Intermediate the target 17 and the coin ejector 4, the plate 24 is steeply inclined as shown at 25. On each side of the inclined portion 25 are inclined plates 26 and 27 which, together with a rear plate 28 and inclined portion 25, form a converging chute 29. The converging chute 29 converges into a portion 30 of more or less uniform diameter. The particular construction of the members 24, 26, 27, 28 and 30 may be varied considerably. The construction shown is merely for the purpose of illustrating applicant's invention. Rod 120 is provided to flip the coin so that same will fold more or less vertically into portion 30. An additional plate 31 may be provided, if desired, for the purpose of strengthening the structure. At the lower end of the portion 30 is a closure member 32 supported by a member 33 which is pivoted at 34. The opposite end of the member 33 is positioned such that same engages notches 35 and 36 in a disk 37. Disk 37 is connected to clock mechanism (not shown) and members 33 and 37 are for the purpose of placing same in motion and stopping same. Below the portion 30 is a chamber 38 for the collection of coins dropping down through chute 29. Door 3 is provided with suitable lock 39 and lugs 40; thus making same removable by persons possessing a key to lock 39. Coins dropping into chamber 38, of course, are extracted through door 3. Disk 37 is mounted on the shaft 41. Disk 37 may be of the form shown in Fig. 5. Disk 37 is shown with an annular groove 42; thus forming flanges 43 around the circumferential edges of disk 37. The notches 35 and 36 are formed by cutting away portions of the flanges 43. The member 33 may have an angular portion 33' as shown in Fig. 5. The end portion of 33' which engages the disk 37 may have a plate 44 attached thereto. The clock mechanism heretofore referred to

is preferably contained within a casing 45. The member 33 may extend through a portion of the casing 45 as clearly shown in Fig. 5, if desired. The shaft 44 extends through the sides of the casing 45 and connects to the clock mechanism or spiral spring tending to turn the shaft 41 in a counter clockwise direction with respect to Fig. 7. It is thus seen that the shaft 41 is held from turning by means of the plate 44 on the arm 33' engaging either one of the notches 35 or 36. At the outer ends of shaft 44 are attached disks 46 and 47. The disks 46 and 47 have arms 48 and 49, respectively, pivoted thereto adjacent the circumference thereof. The pivot 50 on the disk 46 is staggered with respect to the pivot 51 on the disk 47. Pivots 50 and 51 are preferably 180° apart with respect to the shaft 41. The purpose of this is that the articles vended will be ejected alternately from each side of the casing. The front 52 of casing 1 is attached to the front edge of bottom 53 of casing 1 by means of lugs 54 engaging flanges 55 on the bottom of the edge. There is preferably one lug 54 on each side of casing 1. Attached to the front 52 of casing 1 is a plate 56. Plate 56 upon its longitudinal edges is formed with a recess 57. Above recess 57 is attached a plate 58. A groove is thus formed which accommodates one edge of an article ejector 59 or 60. Attached to opposite sides of casing 1 opposite the recesses 57 and plates 58 are members 61 and 62 recessed similar to the longitudinal edges of the plate 56. Above the recesses in members 61 and 62 and attached to the members 61 and 62 are plates 63 and 64, respectively. Members 61 and 63 form a guide for one edge of article ejector 59 and members 62 and 64 form a guide for one edge of the article ejector 60. Arm 48 is attached to article ejector 59 and arm 49 is attached to article ejector 60. On opposite sides of the inner face of front 52 are vertical chutes 65. Chutes 65 are directly above the outer edges of article ejectors 59 and 60. Chutes 65 are preferably rectangular in cross section in the preferred form and hold rectangular articles of relatively small thickness such as gum, pieces of chocolate, etc. However, the shape of these chutes may be varied to suit practice. At the bottom of each chute is an aperture 66 in the front wall 52. A shield 67 is preferably attached to the inner wall of front 52, same having an extension 68 which extends downward over a portion of the aperture 66 in order that only one article will be dispensed at a time. The extreme forward position of article ejector 60 is shown in Fig. 10, the same being shown extending into the aperture 66 under the shield 67. A half revolution of the disk 37 will bring article ejector 60 rearward thus allowing another article to be dispensed to fill the space occupied thereby. A second half revolution of the disk 37

will cause article ejector 60 to eject said article outward through the aperture 66, same dropping into the receptacle 5. In the front 52 opposite the chutes 65 may be positioned longitudinally extending vertical transparent panels 69. These panels are for the purpose of showing whether or not the machine has therein, a supply of articles to be vended. The front 52 may be provided with a lock 70 10 at its upper edge.

The construction of the coin ejector is as follows: Referring to Figs. 12, 13 and 14, coin ejector 4 consists of two body casing members 71 and 72 secured together and 15 shaped to assimilate a pistol. A front sight is provided at the forward end. Casing 72 is shown in Fig. 13. Casing 72 has a channel 73 extending longitudinally thereof. Channel 73 accommodates plunger 74. 20 Plunger 74 is held in channel 73 by means of a flat member 75 secured to casing 72 by suitable screws 76. Plunger 74 is offset at 77 in order to pass between member 75 and casing 72 in channel 73. Plunger 74 has a pin 78 25 extending from the face thereof, said pin in its forward position engaging notch 79 in member 75. Casing 72 has a recess 80. At the forward end of recess 80 is a pin 81 which supports one end of spring 82. The other 30 end of spring 82 is attached to pin 83 on plunger 74. Plunger 74 is held in the position shown in Fig. 13 due to the action of spring 82. Plunger 74 is actuated as follows: Trigger 84 is pivoted at 85 to casing 35 72. At the inner end 86 of trigger 84 is pivoted a link 87. Link 87 is pivoted to a link 88 at 89. Link 88 is pivoted to casing 72 at 90. Trigger 84 is held in the position shown in Fig. 13 by means of spring 91 attached to 40 link 87 at 92 and attached to casing 72 at 93. At the other end of link 88 opposite the pivot 89 is a pivoted catch member 94 for the purpose of engaging the pin 95 on the plunger 74. The catch member 94 has an inwardly 45 projecting finger 96 thereon which engages one side of link 88 in order that catch member 94 will be held in the position shown in Fig. 13 by spring 97 which is attached thereto. Catch member 94 has an inwardly projecting 50 portion 98 (see Fig. 12) for engaging the pin 95. In operation, on pulling the trigger 84, member 94 rises to engage pin 95 pulling plunger 74 to the left with respect to Fig. 13. Catch member 94 eventually rises high 55 enough to disengage the pin 95 allowing same to move forward under the action of the spring 82. It is this force which ejects the coin from the coin ejector. In casing 72 on each side of the channel 73 are shoulders 100 60 and 101. Shoulders 100 and 101 are oppositely arranged in order to form a continuous channel for a coin. The other face of this channel is closed by the casing member 71. The coin is inserted in a slot 102 (see Fig. 65 14), one face of said slot being formed by

the member 75. The member 75 is positioned in a recess in the casing 72 in order that same is flush with the shoulders 100 and 101. The coin is placed in the slot 102 and drops downward onto pin 78. It is thus only partially inserted. However, when the plunger 74 is drawn back slightly by pulling on the trigger 84, the coin drops all the way into slot 102 and is in line to be ejected through the slot formed by shoulders 100 and 101. The reason for first supporting the coin on the pin 78 is for the purpose of sighting. The coin protrudes slightly above the slot 102 for this purpose.

The operation of the device is as follows: 80 The coin is placed in slot 102 of coin ejector 4 as previously explained. After sighting in an effort to have the coin pass through aperture 18, the trigger 84 is pulled backward and the coin ejected from the slot formed by shoulders 100 and 101 and casing 71. Should the coin pass through the aperture 18, same will be returned to the prospective purchaser by means of chute 21. The coin drops through aperture 8 into receptacle 7. No sale 85 is made in this instance. Should the coin strike the target 17 and not pass through the aperture 18, same will drop downward into chute 29, pass outward through member 30 engaging the closure member 31; thus actuating arm 33. Plate 44 is disengaged from either notch 35 or 36 on disk 37 momentarily and disk 37 makes one-half revolution. The arm 33 is weighted in order that the closure member 32 will return to its original position. 90 Thus, the plate 44 will engage the next notch in disk 37. During the half revolution of the disk 37, shaft 41 turns one-half revolution and one article is pushed forward out through an aperture 66 in the front wall 52 and into a 95 receptacle 5. In this case, a sale has been made. It is thus seen that amusement is provided for the prospective purchaser. The extent of the amusement for each sale is determined by the skill and marksmanship of the prospective purchaser. The coins falling into chamber 38 are withdrawn by removing door 3. Chutes 65 are filled by releasing the latch of lock 70 with a key and drawing the front wall 52 of casing 1 slightly forward. 100 The glass panel 15 above the coin ejector 4 is preferably spaced from the coin ejector. In order to allow free movement of the coin ejector. It is also preferable to sight under the glass panel 15, however, it is also possible to sight through the glass if same is brought down close to the top of the ejector.

Having thus described my invention, it is obvious that various immaterial modifications may be made in the same without departing from the spirit of my invention; hence I do not wish to be understood as limiting myself to the exact form, construction, arrangement and combination of parts herein shown and described, or uses mentioned.

What I claim as new and desire to secure by Letters Patent is:

1. In a vending machine, a pair of article magazines, a rotatable shaft, means for rotating said shaft, a pair of disks fixedly mounted on the shaft, a reciprocably movable plate for each magazine for ejecting articles therefrom, links connected with said disks and said plates whereby rotation of the shaft reciprocally moves the plates to eject articles alternately from said magazines, and means for locking said shaft against rotation.
2. In a vending machine, a pair of article magazines, a rotatable shaft, means for rotating said shaft, a pair of disks fixedly mounted on the shaft, a reciprocably movable plate for each magazine for ejecting articles therefrom, links connected with said disks and said plates whereby rotation of the shaft reciprocally moves the plates to eject articles alternately from said magazines, and means for locking said shaft against rotation, said locking means including a third disk fixed on the shaft and having diametrically opposite notches in its periphery, and a pivotally mounted lever normally having one end thereof operatively engaging one of said notches to form a stop preventing rotation of the shaft and disks.
3. In testimony whereof, I have hereunto signed my name.

HAROLD GREENHILL.
